HUB CONSTRUCTION.

Application filed January 24, 1920. Serial No. 353,808.

This invention relates to hub constructions for demountable wheels, pertaining more particularly to constructions adapted for use in connection with wire wheels.

5 The present invention is designed to meet general conditions by the use of a hub construction which is simple and efficient in operation, durable in construction and which can be manufactured at a relatively low 10 cost. In addition, the construction is such as to provide for the use of practically two elements one of which remains permanently positioned as the inner hub member, the other being demountable as a unit, these two 15 members carrying the entire construction for producing the efficient wheel support action as well as to secure the proper maintenance of the demountable parts in the presence of service conditions, and yet capable of being 20 demounted in a simple manner and without possibility of losing or displacing loose parts, the two members carrying all of the structural elements in such manner as not to 25 be capable of being lost.

To these and other ends, therefore, the nature of which will be readily understood as the invention is hereinafter disclosed, said invention consists in the improved construction and combination of parts, as more fully 30 described hereinafter, illustrated in the accompanying drawings, and more particularly pointed out in the appended claims.

In the accompanying drawings, in which similar reference characters indicate similar 35 parts, in each of the views,

Figure 1 is a longitudinal section of a hub construction according to the present invention, the parts being broken away for clearness;

40 Fig. 2 is an end elevation of the same; Fig. 3 is a side elevation of the outer end portion of the inner hub member;

Fig. 4 is an end view of the member shown in Fig. 3;

45 Fig. 5 is a view, partly in section and partly in elevation of a cap construction forming part of the present invention;

Fig. 6 is a fragmentary view in end elevation of the cap of Fig. 5.

50 Fig. 7 is a view in front elevation of a resilient locking member;

Fig. 8 is an end view of the construction of Fig. 7.

In the drawing, —a— indicates a drive element of suitable type, such for instance 55 as the drive axle of an automobile, the axle being mounted in the usual housing, the latter being indicated at —a'—, and carrying one of the elements of a roller bearing structure, indicated generally at —b—. —c— 60 indicates a member mounted on the axle —a— and driven thereby, said element —c— being adapted to have a splined engagement with the inner hub member 10, the latter having splines arranged on its interior in 65 complementary relation to splines carried by member —c—. The hub member 10 carries an internal flange 10^a which, in connection with the outer member of the bearing —b— serves as a part of the general structure for 70 retaining the inner hub member 10 in its position on the axle housing —a'—. This particular construction is more or less illustrative, it being readily understood that various ways of supporting an inner hub member 75 permanently and rotatably on an axle housing and operatively connecting the hub member with the drive shaft or axle, may be employed, it being understood, of course, that the inner hub member remains as a 80 permanent part of the completed assembly, and that the particular method of driving this hub member may be greatly varied.

So far as the present invention is concerned, the particular portions of the inner 85 hub member 10 entering into the specific form of the invention are the rear annular seat 11, the outer end formation, and the spline formation which cooperates with the outer hub member 12. As shown in Fig. 1, 90 the seat 11 is located adjacent the inner end of the outer hub member, the latter having a complementary face, 12^a, which seats on the seat 11 when the hubs are assembled. The seat 11 is preferably more or less conical and 95 of suitable length axially, while face 12^a is of complementary formation with an axial length in excess of that of seat 11. In practice, the seat 11 is located within the zone defined by the planes at the opposite sides of 100 the rim (not shown), so that it acts as the support for radial stresses, it being understood that the sets of spokes indicated at —e— and —d— are to be considered practically as spokes primarily designed for radial load conditions. This particular ar-

angement of spokes is not claimed specifically herein, since the wheel structure, a portion of which is shown herein, forms the subject matter of a companion application.

5 The outer end portion of the hub member 10 is generally of cylindrical type with its inner face formed with two or more segmental threaded portions 13, these being spaced apart to permit the entrance of complementary threaded portions 14^a of a cap 14, the sections 14^a being freely insertable within these spaces, and angular movement of the cap serves to cause the threaded portions 13 and 14^a to become engaged and thus draw 10 the cap inwardly. As presently pointed out, this inward movement of the cap acts to bring the face 12^a into frictional engagement with seat 11 and serves to bind the two hub members firmly together, this being obtained, 15 by the angular movement of the cap sufficient to properly engage the threaded portions.

To retain the cap in such position, a suitable locking structure is employed, the particular embodiment shown being that of an 20 annular resilient member 15 having laterally extending spring fingers 15^a which are adapted to engage into recesses 10^b of the hub member, the device 15, in this case, being secured to the cap as by rivets or otherwise. Element 15 may be of single thickness but is preferably of a multiple thickness or laminated, and the position of the 25 elements relative to the cap is such that after the cap has been entered and moved 30 angularly to engage the threads, the fingers 15^a will be moved into position within recess 10^b, so that these fingers will act to normally retain the parts in such position. The fingers and the configuration of the 35 recesses 10^b are such that under ordinary service conditions, the cap will be prevented 40 from a retrograde movement sufficient to affect the clamping action produced by the threading of the cap to position. When it 45 is desired to release the parts, a suitable wrench is applied to the end of the cap and by applying considerable pressure angularly exerted the cap may be rotated in the reverse direction, the pressure serving to disengage 50 the fingers 15^a from recesses 10^b, after which the continued rotation of the cap so as to bring its threaded portions 14^a into the recesses between the section 13 will permit the 55 removal of the cap and of the wheel as presently described.

As shown in the drawings, the cap is provided with an annular conical seat 14^b with which a face of the outer hub member contacts, cap 14 having a configuration as will 60 produce a recess into which this outer end of the outer hub member will extend, as shown in Figs. 1 and 5. This result can be produced in different ways, as for instance by spinning down over the hub portion the outer edge portion of the cap, thus locating

the outer edge of the hub portion within an outwardly inclined recess which will serve to prevent detachment of the cap from the hub member and serves to move the hub member in the direction of its axis through 70 the threading movements of the cap.

It will be understood, of course, that this particular connection of hub member and cap is not such as to produce a fixed engagement such as will prevent relative rotative movement between these parts, it being essential, in the particular embodiment shown that such relative rotative movement of the cap be permitted. However, the seat 75 14^b serves to move the hub member to its assembled position by the threading action, and the outer turned over edge of the cap, indicated at 14^c will serve to withdraw the hub member 12 from the tight frictional engagement with the hub member when the 80 cap is unthreaded and then drawn outwardly.

The outer hub member preferably carries a portion 12^c which is slightly conical, with the large end towards the rear of the hub, this portion carrying splines 12^b which cooperate with splines 10^c of the inner hub member, this conical shaped portion 12^c cooperating with the complementary outer faces 90 of the splines 10^c in producing a frictional engagement therebetween, when the parts are assembled, so that not only do the splines 12^b and 10^c operate in providing for the drive action, but this frictional engagement 95 also provides an additional assurance that the two hub members will rotate in unison. Obviously, this arrangement will also permit of ready tightening and loosening of the outer hub member from the splines 10^c by the unthreading movement of the cap. 100

As will be seen, the outer hub member has a set of spokes which extend to a point in proximity to the seat 14^b.

From the above, it will be readily understood that the outer end of hub member 12 is properly seated through the fact that the cap is itself firmly and positively locked to the inner hub member thus assuring the maintenance of the outer hub relative to the axis of the hub, it being understood that the seat 11 located at the opposite end of the hub member performs a similar duty at the opposite hub end, so that both ends of the hub are positively seated in a manner to maintain the true running position of the 115 hubs when the parts are assembled. In addition, the faces 10^c also serve as supports for the outer hub member. 120

From the above it will be seen that there are no parts of the demountable structure 125 which are separable, the cap being firmly attached to the outer hub member and member 15 secured to the cap, so that there is no liability of any parts becoming lost or displaced by the assembling or taking down of 130

the demountable portion of the wheel. Similarly, the permanent portions of the wheel supports which include the inner hub member, also have no loose parts, so that the inner hub practically forms one unit and the demountable portions form a complete unit, these being assembled by the movement of the demountable unit into its position, the cap threaded portion being properly entered and moved to its seated position by the wrench operation to tighten the cap to position. When it is desired to demount the wheel it is necessary only to employ the wrench to rotate the cap itself in the opposite direction, the unthreading movement disengaging the frictional engagement provided by the seat 11 and the faces 10^c leaving the demountable portion free to be easily lifted off when the cap has been rotated the proper distance.

As will be clear, the construction is simple and efficient in operation, the relative arrangement of parts being such as to insure a firm support of the outer hub member when in its assembled position and capable to withstand the stresses and strains which are placed in the wheel when in use. Owing to the location of the various seats and supports between the members, it will be readily understood that the outer hub member need not be of massive formation or of excessively thick material, so that it is capable of being die pressed and thus provide for a low cost of manufacture and at the same time produce the desired strength of structure. Obviously, the construction is such as to provide for durability and long service conditions, since the parts are so arranged as to equalize strains and maintain the integrity of the structure. The formations are such as to permit ready production and the cost of manufacture will be relatively small.

While I have herein shown and described a preferred embodiment of the invention, it will be readily understood that variations and changes therein may be found desirable or essential in meeting the various exigencies of use, and I desire to be understood as reserving the right to make any and all such changes and modifications as may be found desirable or necessary, so far as the same may fall within the spirit and scope of the invention as expressed in the accompanying claims.

Having thus described my invention what I claim as new is:—

1. In hub construction for demountable wheels, wherein an inner hub member is in permanent drive engagement with a drive element, and an outer hub member of sheet metal formation is positionable thereon to rotate therewith as a unit and is removable therefrom to permit wheel demounting, means for detachably securing the inner and outer hub members in such drive engagement

with the inner end of the outer hub member supported directly by the inner hub member and the outer end of the outer hub member supported indirectly by the inner hub member through a cap permanently carried by the outer hub member and detachably engaged with the inner member, said means including a conical seat formation between the inner and outer hub members, a thread formation between the cap and the inner hub member, and a complementary conical seating formation between the outer hub member and the cap to permit cap movement rotatively relative to both hub members and to positively move the outer hub member to and from its driven position by the threading movements of the cap, said cap being imperforate and having a greater diameter than and overlying the outer end of the outer hub member, the outer end of the outer hub member being of greater diameter than the diameter of the portion of such member carrying the intermediate conical seat formation.

2. A hub construction as in claim 1 characterized in that the thread formation between the cap and inner hub member is positioned internally of the inner hub member in the hub assembly to produce a space between the thread portion of the cap and the outer hub member, the cap and inner hub members carrying complementary formations co-operative within such space to normally maintain the cap against retrograde movement.

3. In hub construction for demountable wheels, wherein an inner hub member is in permanent drive engagement with a drive element and an outer hub member is positionable relative to the inner member to rotate therewith as a unit and is removable therefrom to permit wheel demounting with the inner end zones of the inner and outer hub members arranged to produce a conical seating relation therebetween, means for detachably securing said members in the unit drive relation, said means including spline formations located adjacent the outer ends of both members and having complementary faces on the members formed on conical lines with the direction of decreasing diameter opposite that of the direction of movement of the outer hub member in assembly, and a cap permanently positioned on the outer hub member and having threaded portions to engage complementary portions of the inner hub member, threading movements of the cap in opposite directions serving to shift the outer hub member to and from a position of frictional engagement of said complementary faces, whereby the outer hub member is supported by the inner hub member at spaced apart points in the direction of the axis of the members, and the contacting seating faces between the two hub members are wholly of conical type.

4. In hub construction for demountable wheels, wherein an inner hub member is in permanent drive engagement with a drive element and an outer hub member is positionable relative to the inner member to rotate therewith as a unit and is removable therefrom to permit wheel demounting, means for detachably securing said members in the unit drive relation, said means including a cap detachably engageable with the inner hub member, the outer end of the outer hub member having an outwardly flared portion, said cap having a configuration to produce portions extending on opposite sides of the flared portion

5. In hub construction for demountable wheels, wherein an inner hub member is in permanent drive engagement with a drive element and an outer hub member is positionable relative to the inner member to rotate therewith as a unit and is removable therefrom to permit wheel demounting, means for detachably securing said members in the unit drive relation, said means including an imperforate cap permanently carried by the outer hub member, said cap and inner hub member having complementary configurations operative to move the cap in the direction of its axis by cap movement in a rotative direction, said cap-moving configurations being spaced from the outer hub member to produce a space between such configurations and the outer hub member, and complementary means carried by the cap and inner hub member and operative within such space to normally retain the cap in position to maintain the unitary relation of the hub members.

6. In hub construction for demountable wheels, wherein an inner hub member is in permanent drive engagement with a drive element and an outer hub member is positionable relative to the inner member to rotate therewith as a unit and is removable therefrom to permit wheel demounting, means for detachably securing said members in the unit drive relation, said means including an imperforate cap permanently carried by the outer hub member, said cap and inner hub member having complementary configurations operative to move the cap in the direction of its axis by cap movement in a rotative direction, said cap-moving configurations being spaced from the outer hub member to produce a space between such configurations and the outer hub member, and complementary means carried by the cap and inner hub member and operative within such space to normally retain the cap in position to maintain the unitary relation of

the hub members, said latter means being ineffective during movement of the cap to and from such position.

7. In hub construction for demountable wheels, wherein an inner hub member is in permanent drive engagement with a drive element and an outer hub member is positionable relative to the inner member to rotate therewith as a unit and is removable therefrom to permit wheel demounting, means for detachably securing said members in the unit drive relation, said means including an imperforate cap permanently carried by the outer hub member, said cap and inner hub member having complementary configurations operative to move the cap in the direction of its axis by cap movement in a rotative direction, said cap-moving configurations being spaced from the outer hub member to produce a space between such configurations and the outer hub member, and complementary means carried by the cap and inner hub member and operative within such space to normally retain the cap in position to maintain the unitary relation of the hub members, said latter means including an element carried by one of said parts and having a resilient finger adapted to move into and out of engagement with a recess formed in the other of said parts.

8. In hub construction for demountable wheels, wherein an inner hub member is in permanent drive engagement with a drive element and an outer hub member is positionable relative to the inner member to rotate therewith as a unit and is removable therefrom to permit wheel demounting, means for detachably securing said members in the unit drive relation, said means including a cap permanently carried by the outer hub member, said cap and inner hub member having complementary configurations operative to move the cap in the direction of its axis by cap movement in a rotative direction, said cap-moving configurations being spaced from the outer hub member to produce a space between such configurations and the outer hub member, and complementary means carried by the cap and inner hub member and operative within such space to normally retain the cap in position to maintain the unitary relation of the hub members, said latter means including a resilient finger carried by the cap and adapted to be moved into and out of a recess of the inner hub member by rotative movement of the cap, said recess extending inward from the plane of the end face of the hub member.

In testimony whereof I affix my signature.

CLAUDE SAUZEDDE.
